UNITED STATES PATENT OFFICE

ALFRED C. GILBERT, OF NORTH HAVEN, CONNECTICUT, ASSIGNOR TO THE A. C. GILBERT COMPANY, OF NEW HAVEN, CONNECTICUT, A CORPORATION OF MARYLAND

TOY LOCOMOTIVE

Application filed August 29, 1931. Serial No. 560,058.

This invention relates to toy locomotives and particularly to that portion of a locomotive known as a steam chest and cylinder band. The parts of a toy locomotive to which this invention relates are usually furnished as part of a complete set so formed as to be readily assembled together to form various models and types of engines and similar toys. A complete assembly of 10 parts of such a set in the form of a toy locomotive is shown and fully described in my copending application, Serial No. 560,056, filed August 29, 1931.

This invention particularly relates to the 15 structure of the steam chest and cylinder band and their associated or adjacent parts for use with and as part of a toy locomotive of the above type.

One of the objects of this invention is to 20 provide an improved steam chest and cylinder band for a toy locomotive.

Another object is to provide a steam chest and cylinder band assembly having a minimum number of parts in its structure, and 25 which may be readily assembled together into a unit which may be readily assembled to the associated parts of a toy locomotive.

A further object is to provide a toy steam chest and cylinder band, having a plurality 30 of detachably connected parts which may be secured together by means of a minimum number of securing devices and in a simple and efficient manner.

To these and other ends, the invention 35 consists in the novel features and combinations of parts to be hereinafter described and claimed.

In the accompanying drawing:

Fig. 1 is a side view of the front end of a 40 toy locomotive, embodying the features of this invention;

Fig. 2 is a rear end section of a portion of the locomotive showing an end view of the steam chest and cylinder band assembly, 45 certain parts being in section for the sake of clearness;

Fig. 3 is a top plan view of the steam chest and cylinder band shown in Fig. 2;

Fig. 4 is an enlarged section on line 4-4 50 of Fig. 1, and

Fig. 5 is an enlarged section on line 5-5 of Fig. 2.

In the embodiment illustrated the toy locomotive is formed by a plurality of detachably connected parts, among which are 55 boiler sections 10 and 11, front end plate 12, sand box 13, smoke-stack 14, feed water heater 15, hand rail 16, running-boards 17 and 18, apron 19, bumper plate 20, and a cow-catcher 21. A front truck 22 having 60 track engaging wheels 23 and 24, is secured to a main connecting frame 25, to which drive wheels 26, of which only one is shown, are journaled.

Links 27 and 28 are provided which are 65 adapted to swing when the drive wheels 26 rotate, and main connecting rods 30 are suitably connected to the drive wheels 26 and to cross-heads 31 to slide the same upon guides 32 and 33, secured to and extending 70 rearwardly from the steam chest and cylinder band of this invention. Levers 34 and 35 are suitably connected to cross-heads 31 to swing when the latter slide, and to operate levers 36 which are connected to rods 75 37 simulating valve rods and which slide into and out of the steam chest and cylinder band. The cross-heads 31 are connected to rods 38 which also slide into and out of the steam chest and cylinder band when the 80 cross-heads slide.

The rear ends of guides 32 and 33 are secured to guide bar supporting members 39 which are secured to lever supporting members 40, secured to supporting bars 41, suitably attached to the boiler parts 10 and 11. The frame 25 is inverted U-shaped in cross-section and supports the steam chest and cylinder band of this invention upon its upper surface. Toy parts 43 and 44 secured 85 to both the boiler part 11 and the steam chest and cylinder band, and extending from one to the other, are provided to simulate steam pipe casings.

The steam chest and cylinder band assembly comprises a casing body formed by a strip of sheet metal, the intermediate portion 45 of which is disposed horizontally across the frame 25 and is secured thereto by bolts 46 and 47. From each end of portion 95 100

45 the strip is directed downwardly, as at 48, then turned about an arc, as at 49, and directed upwardly, as at 50, to form depending U-shaped portions at the ends of 5 the intermediate portion 45. The strip is then turned about an arc, as at 51, and directed inwardly whereby the ends 52 and 53 of the strip are disposed directly toward each other and spaced above and substantially parallel to intermediate portion 45. 10 The ends 52 and 53 are transversely spaced apart to permit ready access to bolts 46 and 47. Plates 54 and 55, each having a flange 56 about its periphery, are shaped to form 15 end plates for the casing body, the flanges 56 surrounding the edges of the casing body and preventing distortion thereof upon the plates 54 and 55 being drawn toward one another and against the edges of the casing 20 body 45 by bolt 57. By the provision of flanges 56 only one bolt 57 is required to efficiently retain these parts together.

Cup-shaped parts 58 are disposed concentric with the arcuate portions 49 of casing 25 body 45, and are secured to plates 54 and 55 by bolts 59 with the open ends of the cup-shaped parts directed toward and against the respective plates to simulate cylinder heads. The bolts 59 which secure the rearwardly disposed cup-shaped parts 58 to the rear plate 54, also secure the cross-head guides 32 and 33 thereto, the guides 32 and 33 constituting arms which are directed substantially at right angles from connecting 30 portions 60 through which the bolts 59 pass. The portions 60, parts 58 and plate 54, are provided with aligned perforations 60^a through which rods 38 pass into the casing 45 during the movement of the rods 38 by 35 the cross-heads 31. Similar cup-shaped parts 61 are disposed upon plates 54 and 55, concentric to the arcuate portions 51. The cup-shaped parts 61 and plate 54 are provided with aligned perforations to permit 40 rods 37 to slide therethrough under the influence of levers 36.

The toy steam chest and cylinder band assembly described above is relatively simple and is formed of a minimum number of 45 parts which may be readily assembled. These parts may be assembled and retained together by a minimum number of securing devices which are readily accessible and efficient in use.

55 While I have shown and described a preferred embodiment of my invention, it will be understood that it is not to be limited to all of the details shown, but is capable of modification and variation within the spirit 60 of the invention and within the scope of the appended claims.

What I claim is:

1. In a toy locomotive, a steam chest and cylinder band unit comprising a plurality 65 of detachable parts, including a strip of

sheet metal formed to provide a casing body having a flat horizontally disposed portion, and a depending U-shaped portion at each end of said horizontally disposed portion, and a cover plate extending over both depending U-shaped portions at each side of 70 said casing body.

2. In a toy locomotive, a steam chest and cylinder band unit comprising a plurality of detachable parts, including a strip of 75 sheet metal formed to provide a casing body having a flat horizontally disposed portion, and a depending U-shaped portion at each end of said horizontally disposed portion, a plate extending over both depending 80 U-shaped portions on each side of said casing body, each of said plates having a flange about its periphery extending about and over the adjacent edge of said casing body.

3. In a toy locomotive, a steam chest and cylinder band unit comprising a plurality of detachable parts including a strip of sheet metal formed to provide a casing body having a flat horizontally disposed portion, and a depending U-shaped portion at each end 90 of said horizontally disposed portion, a cover plate extending over both depending U-shaped portions at and against each side edge of said casing body, and a single securing means for simultaneously clamping 95 both of said end plates against the respective side edges of said casing body.

4. In a toy steam chest and cylinder band assembly, a casing body formed of a sheet metal strip having an intermediate portion 100 of said strip horizontally disposed, said strip being downwardly directed at each end of said intermediate portion, turned and directed upwardly and then turned and directed inwardly, the end of said strip being 105 disposed substantially horizontally.

5. In a toy steam chest and cylinder band assembly, a casing body formed of a sheet metal strip having an intermediate portion 110 of said strip horizontally disposed, said strip being downwardly directed at each end of said intermediate portion, turned and directed upwardly and then turned and directed inwardly, the ends of said strip being disposed and spaced apart substantially horizontally and spaced above and substantially parallel to said intermediate 115 horizontally disposed portion.

6. In a toy steam chest and cylinder band assembly, a casing body formed of a sheet metal strip having an intermediate portion 120 of said strip horizontally disposed, said strip being downwardly directed at each end of said intermediate portion, turned and directed upwardly and then turned and directed inwardly, the ends of said strip being disposed substantially horizontally, and end plates secured one to each end of said casing body.

7. In a toy steam chest and cylinder band 125

assembly, a casing body formed of a sheet metal strip having an intermediate portion of said strip horizontally disposed, said strip being downwardly directed at each 5 end of said intermediate portion, turned and directed upwardly and then turned and directed inwardly, the ends of said strip being disposed substantially horizontally, end plates secured one to each end of said 10 casing body, and a single securing means to retain said plates in place.

8. In a toy steam chest and cylinder band assembly, a casing body formed of a sheet metal strip having an intermediate portion of said strip horizontally disposed, 15 said strip being downwardly directed at each end of said intermediate portion, turned and directed upwardly and then turned and directed inwardly, the ends of said strip 20 being disposed substantially horizontally, end plates secured one to each end of said casing body, each of said plates having a flange about its periphery and extending about and over the side edges of said casing 25 body, and a single securing means acting upon both of said plates to clampingly draw them into engagement with said casing body.

9. In a toy steam chest and cylinder band assembly, a casing body formed of a sheet metal strip having an intermediate portion of said strip horizontally disposed, said strip being downwardly directed at each end of said intermediate portion, turned and directed upwardly and then turned and directed inwardly, the ends of said strip being disposed and spaced apart substantially horizontally and spaced above and substantially parallel to said intermediate horizontally disposed portion, said horizontally disposed portion having openings provided therein adapted to receive fastening means to secure said casing body to a frame member, said fastening means being accessible 40 through the space between the ends of the strip.

10. In a toy steam chest and cylinder band assembly, a casing body formed of a sheet metal strip having an intermediate portion 50 of said strip horizontally disposed, said strip being downwardly directed at each end of said intermediate portion, turned and directed upwardly and then turned and directed inwardly, the ends of said strip being disposed and spaced apart substantially horizontally and spaced above and substantially parallel to said intermediate horizontally disposed portion, said horizontally disposed portion having openings provided 55 therein adapted to receive fastening means to secure said casing body to a frame member, said fastening means being accessible 60 through the space between the ends of the strip, and a single securing means to retain both of said plates in place.

11. In a toy steam chest and cylinder band assembly, a casing body formed of a sheet metal strip having an intermediate portion of said strip horizontally disposed, said strip being downwardly directed at each end of 70 said intermediate portion, turned and directed upwardly and then turned and directed inwardly, the ends of said strip being disposed and spaced apart substantially horizontally and spaced above and substantially parallel to said intermediate horizontally disposed portion, said horizontally disposed portion having openings provided therein adapted to receive fastening means to secure said casing body to a frame member, said fastening means being accessible through the space between the ends of the strip, end plates for said casing, said plates having flanges about their peripheries which extend about and over the side edges of said 75 casing body, and a single securing means acting upon both of said plates to clampingly draw them into engagement with said casing body.

12. In a toy steam chest and cylinder band assembly, a casing body formed of a sheet metal strip having an intermediate portion of said strip horizontally disposed, said strip being downwardly directed at each end of said intermediate portion, turned and directed upwardly and then turned and directed inwardly, the ends of said strip being disposed and spaced apart substantially horizontally and spaced above and substantially parallel to said intermediate horizontally disposed portion, said horizontally disposed portion having openings provided therein adapted to receive fastening means to secure said casing body to a frame member, said fastening means being accessible 90 through the space between the ends of the strip, end plates for said casing, said plates having flanges about their peripheries which extend about and over the side edges of said casing body, and a single securing means acting upon both of said plates to clampingly draw them into engagement with said casing body.

13. In a toy locomotive, a steam chest and cylinder band assembly comprising a casing body having spaced apart hollow portions and being formed of one piece of strip material, end plates disposed one on either end of said body and extending over both of said hollow portions thereof, and single securing means acting on both of said plates to clamp them against said casing body.

14. In a toy locomotive, a steam chest and cylinder band assembly comprising a casing body formed of one piece of strip material, end plates disposed one on either end of said casing body, single securing means acting on both of said plates to clamp them against said casing body, a cup-shaped member se- 125

cured to the outer face of one of said plates with the open end of said cup-shaped member facing said plate, and a cross-head guide having parallel arms and an arm connecting member disposed with the connecting member against said cup-shaped member, and common means to secure said guide and said cup-shaped member to said plate.

15. In a toy locomotive, a cylinder unit comprising a strip of metal bent to form a casing, said casing including a pair of spaced cylinders, and an end plate for said casing extending over said cylinders and having its peripheral edge shaped to conform to the outline of the casing and included cylinders.

16. In a toy locomotive, a steam chest, a cylinder unit comprising a strip of metal bent to form a casing, including a pair of spaced cylinders and steam chests therefor, and end plates for said casing having their peripheral edges shaped to conform to the outline of the casing.

17. In a toy locomotive, a cylinder unit comprising a strip of metal bent to form a casing, including a pair of spaced cylinders, and an end plate for said casing extending over said cylinders and having its peripheral edge shaped to conform to the outline of the casing and included cylinders, and peripheral flanges on the end plates embracing the casing and included cylinders and holding the walls thereof against unbending movement.

18. In a toy locomotive, a steam chest, a cylinder unit comprising a strip of metal bent to form a casing, including a pair of spaced cylinders and steam chests therefor, end plates for said casing having their peripheral edges shaped to conform to the outline of the casing, and peripheral flanges on the end plates embracing the casing and holding the walls thereof against movement.

19. In a toy locomotive, a frame member, a steam chest, a cylinder band assembly, a cylindrical boiler part extending along said frame member above said steam chest and cylinder band assembly, said latter comprising a casing body formed of a sheet metal strip having a horizontally disposed intermediate portion resting upon said frame member, said strip being downwardly directed at each end of said intermediate portion, turned and directed upwardly and then turned and directed inwardly, and means connecting each of said last mentioned portions of said strip with said cylindrical boiler part.

In witness whereof, I have hereunto set my hand this 25th day of August, 1931.

ALFRED C. GILBERT.
